Arthur Salm Inc., Chicago, Ill., a corporation of Illinois

Filed Aug. 20, 1964, Ser. No. 81,370

Term of patent 14 years

Claims priority, application Germany Apr. 18, 1964

(Cl. D22—5)

FIG. 1 is a perspective view of scissors or the like showing my new design;

FIG. 2 is a top plan view of the scissors of FIG. 1;

FIG. 3 is a side elevational view of the scissors of FIG. 1; and

FIG. 4 is an end view of the handle end of the scissors of FIG. 1.

The side of the scissors opposite that shown in FIG. 2 is similar to FIG. 2 and is plain and unornamented.

I claim:

The ornamental design of scissors or the like, substantially as shown and described.
